UNITED STATES PATENT OFFICE

LUCIEN BÉGIN, OF PARIS, FRANCE, ASSIGNOR OF ONE-HALF TO WILLIAM B. WEAVER, OF BIRMINGHAM, ALABAMA, AND HAROLD F. WILHELM, OF NEW YORK, N. Y.

ELECTRIC SIGNALING.

Application filed July 7, 1926, Serial No. 120,917, and in France July 18, 1925.

This invention relates to electric signaling and particularly to multiplex carrier wave telephony or telegraphy.

One of the principal objects of the invention is the provision of improved means for more effectively eliminating the difficulties encountered in differentiating the different frequencies, for example, the transmitting and receiving waves of a given channel.

Other objects and advantages of the invention will be apparent to one skilled in the art to which the invention relates from the following disclosure in which:

Fig. 1 is a schematic diagram of a system for differentiating a transmitted wave from a received wave and affording absolute non-interference of the transmitted wave on the receiver.

Fig. 2 is a schematic diagram of a system for differentiating a transmitted wave from two received waves of different frequency and affording absolute non-interference of the transmitted wave on the receiver.

Fig. 3 is a schematic diagram of a system for accomplishing the same results as Fig. 1 by the use of different methods.

Fig. 4 is a schematic diagram of a system for accomplishing the same results as Fig. 2 by the use of different methods.

Fig. 5 is a schematic diagram of a system similar to Fig. 4 with the exception that additional means are provided for differentiating the two received frequencies.

Fig. 6 is a schematic diagram of a system somewhat similar to Figures 1 and 3.

Figures 7 to 10 inclusive are schematic diagrams of various systems in which double differentiation between the sending and receiving channels are effected.

It is known that it is possible to effect carrier-wave signaling in duplex, that is to say in a manner similar to that of an ordinary telephone, by means of one and the same carrier-wave frequency providing the transmitter output be made into the transmitting medium differentially with respect to the receiving apparatus also associated therewith, and in such a manner that the receiver will be connected to equipotential points from the point of view of the transmitted waves whilst

remaining in a condition to be operated by the waves emitted by the remote correspondent.

While this method has the advantage of necessitating but a single carrier-wave frequency for each duplex channel, it comprises the disadvantage of necessitating the use of an artificial balancing line which, independently of the fact that it uselessly absorbs half of the transmitting power, is of difficult construction and of unstable operation. For this reason, this system is not widely used and it is generally preferred to sort out the transmitted and received waves mainly by using waves of different frequencies.

This latter method is quite satisfactory when the power involved for transmission does not exceed certain limits with respect to that which is available for operating the receiver and providing transmission takes place on a carrier-wave frequency which is sufficiently different from that of the received waves. Now, in the case where it is desired to simultaneously carry out several duplex communications, this necessary spacing of the various signaling frequencies involves serious difficulties in this that, conditions being otherwise equal, the attenuation of the various channels is widely different depending on their frequencies.

On the other hand when duplex operation is effected at very high frequencies, the power put into play at the transmitter is, for similar reasons of attenuation, necessarily at a much higher level than that available for the operation of the local receiver and the difficulties encountered in sorting out the different waves are consequently increased. The use of electrical resonance phenomena or of filtering circuits, which is usually resorted to, does not enable absolute differentiation and there always exists a certain amount of mutual interference between the various channels.

In accordance with this invention, the elements of the signaling apparatus used for the various one-way channels are serially connected with the transmitting medium and in such a manner that each element is branched across equipotential points with re-

spect to the current flowing through the other elements and this result is arrived at without resorting to balancing arrangements the operation of which is subject to the state 5 of the transmitting medium. The invention moreover enables decreasing the intervals between the frequencies used for the various channels with the consequent advantage of obtaining more uniform attenuation.

10 Referring to Fig. 1, the transmitting apparatus is connected to the winding 120 of transformer 121, one terminal being connected directly to one extremity of the winding and the other terminal being connected 15 to the other extremity of the winding through a rejector 122 and a reactance coil 123, as shown. The rejector 122 comprises the usual reactance coil and condenser in shunt therewith, as shown.

20 One extremity of winding 124 of transformer 121 is connected to one extremity of winding 125 thru resistance 132. The other extremity of winding 124 is connected to the other extremity of winding 125 thru a rejector 126 and reactance coil 127 connected in series therewith, as shown. The rejector 126 is of the usual type, comprising a reactance coil and a condenser in shunt therewith. The receiving apparatus is connected across equi- 25 potential points of the windings 124 and 125, as shown.

30 Winding 128 of transformer 129 is connected to the coupling apparatus, which is in turn connected to the transmitting medium, as shown. The transmitting medium may be the conductors of a power transmission system or may be ordinary telephone or telegraph conductors or may be an antenna, etc.

35 Let f_1 be the received signal frequency or frequency band and f_2 the transmitted frequency or frequency band, the comparative magnitudes of the frequencies being denoted by the subscripts.

40 Rejectors 122 and 126 are arranged to offer a large impedance to f_1 . These rejectors will therefore offer a small capacity reactance to f_2 . This is neutralized by the inductive reactance of coils 123 and 127. The rejectors 45 offer substantially zero impedance to f_2 and very small resistance thereto. The resistance to f_2 offered by rejectors 126 is exactly balanced by resistance 132.

45 This system functions in the following manner. The transmission frequency f_2 is easily conveyed to the transmission medium thru transformers 121, 129 and the coupling apparatus, in view of the fact that rejectors 122 and 126 offer substantially zero impedance, thereto. Owing to the fact that the receiving apparatus is connected across equi-potential points of coils 124 and 125, as far as f_2 is concerned, current of frequency f_2 will not influence said apparatus.

50 Now assume that receiving frequency f_1

55 makes its appearance in coil 125. Rejector 126 precludes the passage of this frequency thru the lower parts of coils 124 and 125. Current of frequency f_1 may now flow thru the receiving apparatus as the points which were at equal potential for frequency f_2 are not at frequency f_1 . It is of course to be understood that both transmission and reception may go on separately or simultaneously, the separate functioning being described for 70 the sake of simplicity. Rejector 122 prevents the received frequency f_1 from influencing the transmitting apparatus.

60 Referring to Fig. 2, in which like numerals indicate similar parts, the receiving apparatus is arranged to receive frequencies f_1 and f_3 ; while the transmitting apparatus is arranged to transmit frequency f_2 . Frequency f_2 is halfway between frequencies f_1 and f_3 .

65 One terminal of the transmitting apparatus is connected to one extremity of coil 120 of transformer 121 through rejector 122. The other terminal of the transmitting apparatus is connected to the other extremity of coil 120 through rejector 130, as shown. Rejector 122, rejects f_1 while rejectors 130 reject f_3 . The transmitting apparatus is therefore not influenced by received frequencies f_1 and f_3 . The rejectors 122 and 130 together are tuned 75 to the transmitted frequency f_2 .

70 One terminal of coil 124 is connected to one terminal of coil 125 through two rejectors 126 and 131, the said rejectors being connected in series with each other as shown.

75 Another terminal of coil 124 is connected to another terminal of coil 125 through a resistance 132. The terminals of coil 128 are connected to apparatus similar to that described in connection with Fig. 1, as shown.

80 Rejector 126 rejects frequency f_1 while rejector 131 rejects f_3 , the two together offering substantially zero impedance to the transmitted frequency f_2 . Resistance 132 equals and balances the resistance offered to frequency f_2 by rejectors 126 and 131.

85 This arrangement functions in a manner similar to that described above in connection with Fig. 1, the only difference being the arrangement is capable of receiving two frequencies. Due to the fact that the receiving apparatus is connected across equi-potential points as far as the transmitted frequency is concerned, it is non-influenced thereby.

90 Referring to Fig. 3 in which like numerals indicate similar parts, one terminal of the transmitting apparatus is connected to one terminal of the coupling apparatus thru resistance 133, as shown. The other terminal of the transmitting apparatus is connected to the other terminal of the coupling apparatus thru a reactance device 134, as shown. Reactance device 134 comprises a rejector 135 and a condenser 136 connected in series therewith, as shown.

The rejector 135 rejects received frequency f_2 ; but permits the easy passage of transmitted frequency f_1 . The slight inductive reactance offered to f_1 is neutralized by condenser 136. The reactance device will offer a certain amount of resistance to the passage of the transmitted frequency f_1 . This resistance is balanced by resistance 133.

10 A resistance device 137 and a resistance 138 are connected in series with each other immediately across the terminals of the transmitting apparatus, as shown. The reactance device 137 comprises a rejector 139 and an inductive reactance 140 connected in series 15 with each other, as shown.

A reactance device 141 and a resistance 142 are connected in series with each other immediately across the terminals of the coupling apparatus, as shown. The reactance device 141 comprises a rejector 143 and an inductive reactance 144 connected in series therewith, as shown.

The rejectors 139 and 143 reject the transmitted frequency f_1 ; but permit the easy passage of the received frequency f_2 . The capacity reactance offered to f_2 by rejectors 139 and 143 is neutralized by inductive reactance coils 140 and 144, respectively.

One terminal of the receiving apparatus 30 is connected between resistance 138 and reactance device 137, as shown. The other terminal is connected between resistance 142 and reactance device 141, as shown. The connections constitute equi-potential points for the 35 receiving apparatus with respect to the transmitted frequency f_1 ; but are not with respect to the received frequency f_2 .

In view of the fact that it is impossible 40 to realize pure reactances devoid of resistance, the reactance devices 137 and 141 will give rise to a slight conductance when functioning as rejectors and to a slight effective resistance when functioning as short circuits. Resistances 138 and 142 are arranged 45 to neutralize the leakage of reactance devices 137 and 141, respectively, at frequency f_1 . The resistances 138 and 142 may be connected in series with coils 140 and 144, respectively, so that the small currents which they absorb 50 at frequency f_1 may also show the same phase angle as that absorbed by the reactance devices.

This arrangement functions in the following manner: Rejectors 139 and 143 prevent 55 the passage of the transmitted frequency f_1 thru the receiving apparatus; while rejector 135 permits the passage of f_1 to the coupling apparatus. As the receiving apparatus is connected across equi-potential points with 60 respect to f_1 , it is not influenced thereby. As the rejector 135 prevents the passage of f_2 , the receiving apparatus is no longer connected across equi-potential points with respect to received frequency f_2 and is influenced thereby. Rejector 135 prevents the

transmitting apparatus from being influenced by the received frequency f_2 . It is to be understood that transmission and reception may go on simultaneously.

Referring to Fig. 4, in which like numerals indicate similar parts, one terminal of the transmitting apparatus is connected to one terminal of the coupling apparatus thru balancing resistance 145, as shown. The other terminals are connected together thru 75 rejectors 146 and 147, the said rejectors being connected in series as shown. Rejector 145 is arranged to reject received frequency f_1 ; while rejector 147 is arranged to reject received frequency f_3 . The two rejectors together are therefore resonant to transmitted frequency f_2 , said frequency being intermediate between that of f_1 and f_3 . Rejectors 146 and 147 naturally offer a certain amount of resistance to f_2 . This is balanced by resistance 145.

A reactance device 147a and a large resistance 148 are connected in series with each other immediately across the terminal of the transmitting apparatus, as shown.

20 A reactance device 149 and a resistance 150 are connected in series with each other immediately across the terminals of coupling apparatus, as shown.

25 Reactance device 147a comprises a rejector 151 and an inductive reactance 152 connected in series therewith, as shown. Reactance device 149 comprises a rejector 153 and an inductive reactance 154 connected in series therewith, as shown. Rejectors 151 and 153 100 prevent the passage of f_2 ; but permit the easy passage of f_1 and f_3 . Coils 152 and 154 and resistances 148 and 150 perform similar functions as coils 140 and 144 and resistances 138 and 142 in Figure 21.

30 The terminals of the receiving apparatus are connected across equi-potential points in so far as the transmitted frequency f_2 is concerned; but are not so connected with respect to received frequencies f_1 and f_3 . As the functioning of this system is similar to that of Fig. 21, the only difference being the possibility of reception of two frequencies, a detail description of the same is thought to be unnecessary here.

35 Referring to Fig. 5, in which like numerals indicate similar parts, a system is disclosed for separating the received frequencies f_1 and f_3 from each other. This system is substantially a combination of the systems disclosed in Figures 3 and 4. A detailed description of the same is therefore thought to be unnecessary here.

40 Referring to Fig. 6, which combines in part the systems shown by Figures 1 and 3 and in which like numerals indicate similar parts, one terminal of transmitting apparatus is connected to the mid-point of winding 125 155 of transformer 156, as shown. The other 130

terminal is connected to the extremities of winding 155 as shown.

One extremity of winding 157 is connected to one extremity of winding 158 thru resistance 126, as shown. The other extremity of winding 157 is connected to the other extremity of winding 158 of transformer 159 thru rejectors 126 and inductive reactance coil 127, connected in series therewith, as shown. Rejector 126 rejects the received frequency f_1 ; but permits the easy passage of the transmitted frequency f_2 . Coil 127 neutralizes the slight capacity reactance offered to f_2 by rejector 126. Resistance 132 balances the resistance offered to f_2 by rejector 126 and coil 127.

A rejector device 134 is connected between the upper extremity of winding 157 and its mid-point. This device comprises a rejector 135 and a condenser 136 connected in series therewith, as shown. Rejector 135 rejects f_2 but permits the easy passage of f_1 . The slight inductive reactance offered to f_1 is neutralized by condenser 136. A resistance 160 is connected across the lower extremity of coils 157 and its mid-point as shown. The terminals of the coupling means are connected to the mid-points of coils 157 and 158, as shown. Coil 161 is connected to the receiving apparatus, as shown.

This system functions in the following manner: Current of frequency f_2 passes upward in upper half of coil 157, thru resistances 132, downward in upper half of coil 158 to one terminal of the coupling means and thence to the mid-point of coil 157 thereby completing a circuit.

Current of frequency f_2 also passes downward in lower half of coil 157, thru rejector 126, reactance coil 127, thence upward thru lower half of coil 158 to one terminal of the coupling means and from the other terminal of the coupling means to the mid-point of coil 157. It is to be noted that currents are flowing in opposite directions in coil 158. This results in zero currents in coil 161 and the consequent elimination of interference on the receiving apparatus by the transmitted frequency f_2 .

On the other hand currents of frequency f_1 will flow from one terminal of the coupling means thru rejector device 134, thru resistance 132, downward in the upper half of coil 158 and thence to another terminal of the coupling means. No current of frequency f_1 will pass thru lower half of coil 158 owing to rejector 126. The receiving apparatus will therefore be influenced by f_1 . The transmitting apparatus will not owing to the fact that no current of f_1 flows thru coil 157 due to rejectors 126 and 135.

It will be noted that, in all the figures so far described, the discrimination is absolute but in one direction, i. e., there is only the receiving apparatus which is completely

shielded from the disturbances caused by the local transmitter, the latter being protected from the received waves in a relative manner only, depending on the efficiency of the rejectors and short-circuits used. These conditions may suffice in numerous cases but it will be advisable, in many other cases, to carry out the double differentiation. This has been represented diagrammatically in Figures 7, 8, 9 and 10.

Referring to Fig. 7, one terminal of the coupling means is connected to the mid-point of winding 165 of transformer 166. The other terminal is connected to the mid-point of winding 167 of transformers 168, as shown.

The upper extremity of winding 165 is connected to point 169 thru resistance 170, as shown. The lower extremity of winding 165 is connected to point 169 thru reactance device 171. Reactance device 171 comprises a rejector 172 to the transmitted frequency f_2 and a condenser 173 in series therewith for neutralizing the slight inductive reactance offered to the received frequency f_1 , rejector 172 being a substantial short circuit to f_1 . Resistance 170 balances the resistance to f_1 offered by the reactance device 171. The mid-point of coil 165 and point 169 are therefore equi-potential points for f_1 ; but are not for f_2 .

The upper extremity of winding 167 is connected to point 174 thru a resistance 175. The lower extremity of coil 167 is connected to the point 174 thru a reactance device 176. Reactance device 176 comprises a rejector 177 to the received frequency f_1 and an inductive reactance coil 178 connected in series therewith, as shown. Rejector 177 permits the easy passage of f_2 and inductive reactance coil 178 neutralizes the capacity reactance offered to f_2 . The resistance 175 balances the resistance offered to f_2 by the reactance device 176. Point 174 and the mid-point of winding 167 are equi-potential points for f_2 ; but are not for f_1 . Points 169 and 174 are connected together as shown.

Winding 179 of transformer 166 is connected to the transmitting apparatus; while winding 180 of transformer 168 is connected to the receiving apparatus, as shown.

This system functions in the following manner. Equal currents of received frequency f_1 , flow upward and downward thru upper and lower half, respectively, of winding 165 to point 174. These currents therefore, will exert no influence on winding 179 and consequently none on the transmitting apparatus.

Currents of f_1 can not flow thru rejector 177; but they do flow downward thru upper half of winding 167 and thence back to the coupling means. These currents influence winding 180, which in turn influence the receiving apparatus. In a similar manner, transmitted frequency f_2 passes on to the cou-

pling means; but does not affect the receiving apparatus. However it is to be understood that with this arrangement transmission of f_1 and reception of f_2 may be effected.

5 Referring to Fig. 8, in which the same numerals indicate similar parts, one terminal of the coupling means is connected to equi-potential point 181 with respect to transmitted frequency f_2 thru a resistance 175 and 10 to equi-potential point 182 thru a reactance device 176, as shown.

15 Reactance device 176 rejects f_1 ; but permits the easy passage of f_2 and offers substantially zero reactance to f_2 ; resistance 175 balances the resistance of 176 to f_2 .

Point 181 is connected to point 183 through another reactance device 176 as shown. Point 182 is connected to point 183 through a resistance 175. The terminals of the receiving 20 apparatus are connected across points 181 and 182. These points are equi-potential points with respect to f_2 ; but are not with respect to f_1 .

25 Point 184 is connected to point 185 through a reactance device 171 and to point 186 through a resistance 170. Point 185 is connected to point 187 through a resistance 170 and point 186 is connected to point 187 through a reactance device 171. Points 183 30 and 184 are connected together, as shown. The transmitting apparatus is connected across point 185 and 186, as shown.

35 Reactance devices 171 and resistances 170 make equi-potential points out of points 185 and 186 to f_1 ; but not to f_2 . Point 187 is connected to the other terminal of the coupling means, as shown.

40 It is obvious that the received frequency f_1 does not influence the transmitting apparatus; nor does the transmitted frequency f_2 influence the receiving apparatus.

45 Referring to Fig. 9, in which the same numerals indicate similar parts, this system is somewhat similar to that of Fig. 26 with the exception that two frequencies f_1 and f_3 may be received and one f_2 transmitted. Reactance devices 195 reject f_1 but act as short circuits to f_2 and f_3 . The receiving apparatus for f_1 is therefore connected across 50 equi-potential points in so far as f_2 and f_3 are concerned. It is therefore only influenced by f_1 and not by f_2 and f_3 . Resistances 196 balance the resistances offered by reactance devices to f_2 and f_3 .

55 Reactance devices 197 function as short circuits to received frequencies, f_1 and f_3 , and open circuits to transmitted frequency f_2 . They offer zero reactance to f_2 . The transmitting apparatus is therefore connected across equi-potential points in so far as f_1 and f_3 are concerned and is non-influenced thereby; but is influenced by transmitted frequency f_2 .

60 65 Reactance devices 199 function as short circuits to f_1 and f_2 and open circuits to f_3 .

They also offer zero reactance to f_3 . Resistances 200 balances the resistances offered to f_1 and f_2 by reactance devices 199. The receiving apparatus for f_3 is therefore connected across equi-potential points in so far as 70 f_1 and f_2 are concerned and is non-influenced thereby; but is influenced by f_3 .

Figure 10 shows an extension of the diagram of Fig. 7 to a network comprising the optional use of any two of the frequencies 75 f_1 , f_2 , f_3 . The operation is obtained by associating the transmission medium with any two of the terminals a , b , c . The circuit cells leading to the latter could, for that matter, be connected in series with each other as in 80 Figure 9 and it would then only be necessary to short-circuit that cell which it would not be intended to use at any given moment.

It will be possible to connect together any number whatever of such cells or elements, 85 Figures 9 and 10 showing but three merely by way of example. Those arrangements will be particularly useful in the case of a party line comprising several stations such as A, B, C, etc., and in which the various stations 90 must be able to communicate with one another. Each station will be assigned but a single distinct transmitting frequency and as many receiving frequencies as there are other stations in the network. Station A 95 will transmit, for example, on frequency f_1 and its receiver will be simultaneously or alternately connected at f_1 and f_3 . In that case, station B will always have its transmitter branched at f_2 and will receive indiscriminately at f_1 or f_3 according to the station 100 with which he desires to communicate. Likewise, station C will transmit at f_3 and receive at the inside terminals of the cells assigned to frequencies f_1 and f_2 by short-circuiting 105 or switching out of circuit that or those circuit cells which do not correspond to the frequency transmitted by his correspondent at that instant.

For that matter, it will be possible to combine the use of the single-frequency duplex method described in the preamble thereof together with the schematic diagram described with reference to Figures 7 and 8, by 110 branching a complete single frequency duplex set across the inside terminals of each circuit cell so as to permit of separating the different duplex channels rather than the transmitted and received wave-lengths of a 115 given two-way channel.

120 The schematic diagrams shown in Figures 1, 2, 3, 4, 5 and 6 which comprise absolute selection but in one direction, may also be used for reception purposes only, particularly in the case of several simultaneous receptions, one of which is much stronger than the others and which would be connected to the terminals so far allotted to the transmitter. The weaker reception would thus be shielded 125 from the stronger ones.

It goes without saying that the intermediate-tap transformers shown in the various figures may be substituted by two separate transformers mounted in series or by mere impedances. It will be advisable, however, to make use of transformers or auto-transformers having reduced magnetic leakage between windings and portions of windings not only with a view of decreasing the losses but mainly in order to reduce the inductance thereof when they operate differentially. These inductance effects may furthermore be compensated by suitable capacities inserted in series therewith in order to bring back the current into phase with the voltage.

It should be understood that the reactance networks are purely representative and that they may be substituted by their equivalents as regards operation, it being given that they always operate approximately either as very large resistances (rejectors) or very low resistances (resonant shunts).

While I have disclosed various preferred modifications of my inventions, I do not limit myself to the same; but may employ such other modifications as come within the spirit and scope of my inventions.

I claim:

1. In a communication system for simultaneously sending messages in opposite directions, a communication channel, transmitting apparatus transmitting on a first given frequency and receiving apparatus receiving on a second given frequency connected to the same end of said channel as said transmitter, means whereby said receiving apparatus is connected across equipotential points with respect to said transmitting frequency and said transmitting apparatus is connected across equipotential points with respect to the receiving frequency sent over said channel to said receiving apparatus from a distant station.

2. In a signaling system for simultaneously sending messages in opposite directions, a communication channel, transmitting apparatus and receiving apparatus at the same end of said channel, means for placing said receiving apparatus at equipotential points with respect to energy from said transmitting apparatus, and means for placing said transmitting apparatus at equipotential points with respect to energy from the distant signal received over said channel.

LUCIEN BÉGIN.
